DESIGN.

J. B. GEORGE.

CARPET.

No. 15,392.

Patented Sept. 9, 1884.

UNITED STATES PATENT OFFICE.

JOHN BELLAMY GEORGE, OF 37 Highbury Hill, County of Middlesex, England, assignor to WILLIAM MANSELL DAINTRY, OF NEW YORK, N. Y.

DESIGN FOR A CARPET.

SPECIFICATION forming part of Design No. 15,392, dated September 9, 1884.

Application filed June 30, 1884. Term of patent 3½ years.

To all whom it may concern:

Be it known that I, JOHN BELLAMY GEORGE, a resident of No. 37 Highbury Hill, in the county of Middlesex, England, have invented and produced a new and original Design for a Carpet, of which the following is a full description, in connection with the accompanying photograph, which represents a face view of my new design for a carpet.

10 This invention relates to a new ornamentation of the face of a carpet, oil-cloth, or analogous fabric.

In the accompanying photograph are represented the various parts which enter into 15 my new design.

The stripe A contains representations of ornamental flowers *aa*, somewhat resembling the flowers of the chrysanthemum-plant, the stems of said flowers starting from an ornamental band, *b*, and bearing deeply-serrated leaves. A row of arches, *c c*, is placed above the flowers *aa*, the arches being joined to each other by a rosette, from which an ornamental flower, *d*, with a set of leaves at its stem, rises. 25 The stripe A also contains the ornamental band *e*.

The part B contains the ornamental flowers *ff*, resembling somewhat the flowers of the chrysanthemum-plant, having interlocking leaflets, and between them sprays *gg*, with 30 deeply-serrated leaves and buds.

I claim—

1. The design for a carpet, the same consisting of the stripe A, containing the ornamental bands *b* and *e*, the ornamental flowers *aa* and 35 *d d*, and arches *c c*, substantially as shown.

2. The design for a carpet, the same consisting of the part B, having the flowers *ff*, with interlocking leaflets, and sprays *gg*, substantially as shown. 40

3. The design for a carpet, the same consisting of the stripe A and the part B, substantially as shown. 45

This foregoing specification of my invention for new and original design for carpet signed 45 by me this 10th day of March, 1884.

JOHN BELLAMY GEORGE.
